[57] CLAIM

The ornamental design for a plaque or similar article, substantially as shown and described.

DESCRIPTION

FIG. 1 is a front elevational view of a plaque showing my design;

FIG. 2 is a left side elevational view thereof;

FIG. 3 is a bottom elevational view thereof;

FIG. 4 is a rear elevational view thereof on a 1 to 6 scale with respect to FIG. 1.

FIGS. 5 to 8 illustrate a modified form of my new design.

FIG. 5 is a front elevational view of a modified plaque;

FIG. 6 is a left side elevational view thereof;

FIG. 7 is a bottom elevational view thereof;

FIG. 8 is a rear elevational view thereof on a 1 to 6 scale with respect to FIG. 5.

FIG. 1

FIG. 2

FIG. 3

FIG. 4

UNITED STATES PATENT AND TRADEMARK OFFICE
CERTIFICATE OF CORRECTION

PATENT NO. : Des. 252,504

DATED : July 31, 1979

INVENTOR(S) : Walter Gehrig

It is certified that error appears in the above-identified patent and that said Letters Patent are hereby corrected as shown below:

The "DESCRIPTION" of the drawing figures appearing on the title page should be deleted to insert the following therefor:

--- FIG. 1 is a front elevational view of a plaque or similar article showing my new design;

FIG. 2 is a left side elevational view thereof;

FIG. 3 is a bottom plan view thereof;

FIG. 4 is a rear elevational view thereof on a reduced scale. --

Signed and Sealed this

Fourth Day of December 1979

[SEAL]
